(57) **CLAIM**

The ornamental design for a “container lid,” as shown and described.

DESCRIPTION

FIG. 1 is a top, front, and right side perspective view showing my new design for a container lid.

FIG. 2 is a top view of the container lid shown in FIG. 1.

FIG. 3 is a front view of the container lid shown in FIG. 1.

FIG. 4 is a right side view of the container lid shown in FIG. 1.

FIG. 5 is a left side view of the container lid shown in FIG. 1.

FIG. 6 is a rear view of the container lid shown in FIG. 1.

FIG. 7 is another top, front and right side perspective view of the container lid shown in FIG. 1.

FIG. 8 is a top, front, and right side perspective view showing an alternate embodiment of my new design for a container lid.

FIG. 9 is a top view of the container lid shown in FIG. 8.

FIG. 10 is a front view of the container lid shown in FIG. 8.

FIG. 11 is a right side view of the container lid shown in FIG. 8.

FIG. 12 is a left side view of the container lid shown in FIG. 8.

FIG. 13 is a rear view of the container lid shown in FIG. 8; and,

FIG. 14 another top, front, and right side perspective view of the container lid shown in FIG. 8.

The broken lines are for illustrative purposes only and form no part of the claimed design.
